Attorney.

UNITED STATES PATENT OFFICE.

GEORGE WINTER AND ROBERT WINTER, OF MANCHESTER, ENGLAND.

ELECTRICAL SWITCH.

Application filed January 11, 1922. Serial No. 528,394.

To all whom it may concern:

Be it known that we, GEORGE WINTER and ROBERT WINTER, subjects of the King of Great Britain and Ireland, and residents of 5 Manchester, in the county of Lancaster, England, have invented certain Improvements in Electrical Switches, of which the following is a specification.

These improvements relate to electrical 10 plug switches of that type comprising a base plate, and a rotatable plug concentric with the base plate which plug carries radial arms serving as contact pieces to come against fixed contact pieces on the base plate 15 to close the circuit when the plug carrying the pins which are the terminals of the lead and return wires is pushed into the socket.

The object of our present invention is to 20 form a switch of the type above referred to, our invention consisting in the provision and particular combination of parts which will ensure that, when the plug is rotated in order to close the electric circuit, said plug shall be secured to the base plate and cannot 25 be withdrawn until the plug is rotated in the reverse direction and the circuit opened by the separating of the fixed and movable contacts within the switch body.

In carrying our improvements into effect 30 we provide a switch comprising a base plate, a movable socket and a loose plug member, the base plate bearing contact pieces and the socket bearing radial blades to make contact with said pieces and close the circuit when 35 desired. Such parts are known. On the socket or in such a position as to be movable therewith we fix a spring stop, hereinafter referred to as the locking spring, which when the switch is in the "off" position engages 40 the edge of a fixed stop projecting from the base plate, such stop being herein-after referred to as the locking member. The plug has formed with it or fixed thereon in addition to the two pins serving as 45 terminals for the lead and return wires a locking pin so formed that when the plug is pushed into position the three pins enter holes in the socket and the locking pin pushes the locking spring back to allow radial movement of the socket, the locking spring passing behind the locking member, the edge of the locking member entering a transverse slot in the locking pin to keep 50 the parts in the closed circuit position by friction.

We will now fully describe a method of

carrying the invention into effect with reference to the accompanying drawings, in which:—

Figs. 1 and 2 are front and side elevations 60 of the plug;

Figs. 3 and 4 are similar views of the socket bearing the contact arms;

Figs. 5 and 6 are similar views of the base 65 plate and socket; and

Fig. 7 is a sectional view of the switch as a whole, the plug being shown in outline and the switch being in the "closed circuit" position.

In Figures 1 and 2, 1 is a plug of known 70 type having secured to the inner face thereof the locking pin 2 having formed therein the transverse slot 3. 4, 4 indicate pins, which may be circular as shown, or of any cross section other than that of pin 2. They may 75 be split as clearly shown in Figure 2. These pins 4, 4 are the usual plug pins for the lead and return wires.

In Figures 3 and 4, 5 is a socket, the inner 80 face of which is shown in Fig. 3, mounted 80 on a spindle 6, bearing the contact arms 7 and having fitted thereto, the curved plate spring 8 (the locking spring). Figures 5, 6 and 7 show the socket 5 secured to the base 85 plate 9 by means of the screwed spindle 6, and showing holes 10, 11, 11 in the said 90 socket adapted to receive the pins 2, 4, 4 of the plug 1, and also showing clearly in Figure 5, the relative position of these parts on the socket to the usual contact pieces 12 90 borne by the base plate 9, and the contact arms 7 of socket 5 in the open circuit position. The plate spring 8 is shown in dotted lines in Figures 5 and 6. It will be seen that the curved end of the latter normally comes 95 against the edge of a locking member 13 secured to the base plate and prevents movement of the socket 5.

When it is desired to rotate the socket so as to close the circuit, the plug 1 is pushed 100 into position, pin 2 entering hole 10, and split pins 4, 4 entering the holes 11, 11. The end of pin 2 therefore comes against the locking spring 8 thus pushing it back as shown in section Figure 7, and out of contact 105 with the locking member 13. The socket may now be turned clockwise as viewed in Figure 5, the locking spring 8 passing behind the downwardly depending limb of the part 13, to bring the contact arms 7 against 110 the contact pieces 12 carried by the base plate. The slot 3 in locking pin 2 allows of

2
this movement, the downwardly depending end of locking member 13 entering said slot 3. The edge of the locking spring 8, having now passed behind the locking member 13, 5 presses against the rear face of the latter, this is, that face thereof which is the nearer to the base plate, and by friction maintains the socket in the closed circuit position. A helical spring 14 surrounding the spindle 6 and pressing the socket and base plate apart 10 assists this frictional contact between the locking spring 8 on the socket 5 and the locking member 13 on the base plate. The socket and base plate are thus held in their 15 relative positions, to keep the circuit closed. To open the circuit, the plug 1 is turned counter-clockwise as viewed in Figure 5, thus disengaging the contacts 7 and 12, and at the same time moving the locking spring 20 8, from behind member 13 and disengaging the slot 3 of pin 2 from the edge of the said locking member. On the plug 1 being withdrawn, the locking spring 8 resumes its normal position against the edge of locking 25 member 13, thus preventing any radial movement of socket 5 until the plug with its special slotted pin 2, is again inserted.

A wooden case or cover shown in dotted lines at 15, Figure 7, is provided to prevent 30 rotation of the socket by the fingers, and the base and socket may be formed of any suitable material or combination of materials. The plug may be of wood, as is usual, and the metal parts also of the usual metals.

35 We do not confine ourselves to the particular arrangement shown of locking member 13, locking spring 8, and locking pin 2. The part 8 may be for instance a straight, not curved, plate of spring steel or otherwise, and of suitable thickness. Also as a 40 greater precaution against tampering with the switch, the locking member 13 may be provided with two or more downwardly depending members, with a corresponding 45 number of slots 3 in the locking pin 2. Fur-

ther, the pin 2, and of course the hole 10 wherein it fits, may be arcuate or other shape in cross section and the pins 4, 4 and their corresponding holes 11, 11 in the socket of any cross section different from that of pin 2. Again the locking pin 2 need not be slotted but may be formed with a "foot" or projection at right angles thereto which foot, on the spring 8 being pushed back by the locking pin and the plug turned, would engage the rear edge of the downwardly depending edge of locking member 13. 55

The locking pin 2 may serve as the earth-ing pin.

What we claim as our invention and desire to secure by Letters Patent is:—

In an electric switch, a base plate having electrical contacts mounted thereon, an angularly movable socket mounted on said base plate and concentric therewith, electrical contact blades on the socket to make contact with the electrical contacts on the base plate, a downwardly depending L-shaped bracket on the base plate, a plate spring borne by the socket and opposite to an orifice therein and normally resting against the edge of the bracket on the base plate when the switch is in the off position, a plug bearing terminal pins which make electrical contact with the contact blades borne by the socket through orifices in the latter, and a locking pin having a slot therein borne by the socket to press back the plate spring borne by the latter and allow the socket to be rotated when the plug is inserted therein, 75 the short arm of the L-shaped bracket entering the slot in the pin during such rotation to prevent withdrawal of the plug, and the plate spring borne by the socket passing behind said bracket to retain the socket in the 80 "on" position.

In testimony whereof we have hereunto set our hands.

GEORGE WINTER.
ROBT. WINTER.
